[57] CLAIM

The ornamental design for a snowboarding boot sole, as shown and described.

DESCRIPTION

FIG. 1 is a top plan view of a snowboarding boot sole showing my new design;

FIG. 2 is a left side view thereof, the broken lines partially showing a shoe upper in FIGS. 2 through 10 being for illustrative purposes only, forming no part of the claimed design;

FIG. 3 is a right side view thereof;

FIG. 4 is a front view thereof, the top surface partially shown in FIGS. 4 and 5 forming no part of the claimed design;

FIG. 5 is a rear view thereof;

FIG. 6 is a left side view of an alternate embodiment of the design shown in FIG. 6;

FIG. 7 is a right side view on FIG. 6;

FIG. 8 is a front view of FIG. 6;

FIG. 9 is a front view of FIG. 6;

FIG. 10 is a perspective view of FIG. 1; and,

FIG. 11 is a perspective view of FIG. 6.
